(57) CLAIM

The ornamental design for an automobile front grille, as shown and described.

DESCRIPTION

FIG. 1 is a top, front and side perspective view of an automobile front grille showing my new design;

FIG. 2 is a front view thereof;

FIG. 3 is a side view thereof; and,

FIG. 4 is a top view thereof.

The broken lines shown throughout the drawing views are for illustrative and environmental purposes and form no part of the claimed design.
